UNITED STATES PATENT OFFICE.

NICHOLAS S. VEDDER, OF TROY, AND TOBIAS S. HEISTER, OF LANSINGBURG, NEW YORK, ASSIGNORS TO NICHOLAS S. VEDDER.

DESIGN FOR A HEATING-STOVE.

Specification forming part of Design No. 5,158, dated August 1, 1871.

To all whom it may concern:

Be it known that we, NICHOLAS S. VEDDER, of the city of Troy, in the county of Rensselaer and State of New York, and TOBIAS S. HEISTER, of Lansingburg, in said county and State, have jointly invented and produced a new Design for Stoves, of which the following is a specification, reference being had to the accompanying photographic representation of a Franklin stove having our said design.

One part of our invention is the design for the foot N, as fully shown in the accompanying photograph. Another part of our invention is the design for the columns P P, as distinguished by the moldings o o o thereon, all shaped and arranged as represented in the aforesaid photograph. Another part of our invention is the design for the capitals Q Q, as characterized by the ornamented lower parts r r, projecting middle portions s s, and ornamented top parts t t u, all shaped and arranged together so as to appear as represented in the aforesaid photograph. Another part of our invention is the design for the

arch V as distinguished by the parts w, x x, y y, and z z', all shaped and arranged so as to appear substantially as represented in the photograph. Another part of our invention consists of the design for the door A as distinguished by the ornamental surface b, shaped and composed so as to appear as represented in the aforesaid photograph.

What we claim as our invention is—

1. The design for the foot N, as shown.
2. The design for the columns P P, as herein described.
3. The design for the capitals Q Q, as herein specified.
4. The design for the arch V, as herein set forth.
5. The design for the door A, as described.

NICHOLAS S. VEDDER.
TOBIAS S. HEISTER.
